UNITED STATES PATENT OFFICE.

ADOLPH KLEIN, OF NEW YORK, N. Y.

BOX CONSTRUCTION.

Application filed March 9, 1925. Serial No. 14,041.

To all whom it may concern:

Be it known that I, ADOLPH KLEIN, a citizen of the United States, and a resident of the city, county, and State of New York, and whose post-office address is 49 East 90th Street, New York, N. Y., have invented certain new and useful Improvements in a Box Construction, of which the following is a specification.

10 My invention relates generally to a box construction made of a relatively flexible material such as cardboard and more particularly to a box construction having an extension bottom or top.

15 It has been the general practice hitherto in the manufacture of this type of box to form either the cover member or the body member, or both, by first associating a strip of material which is formed to serve as 20 the upstanding side walls with the bottom member either by adhesive or more generally by an adhesive strip secured partly to the side wall strip and partly to the bottom member and then to affix to the composite construction thus formed as by an 25 adhesive a second or supplemental bottom member which is larger than the first mentioned bottom member and which therefore extends beyond the side walls thereof so as 30 to provide the extension bottom.

This method of manufacturing the box is open to a number of objections among which is the increased cost of manufacture, due to the fact that first, an increased 35 amount of material is necessary; second, the box section being made of four parts require added operations for fixedly associating these parts and third, that the box cannot be finished off by an outer covering of 40 predetermined color or design until it has been completed because of the manner of associating these parts.

One of the important objects of my invention is the provision of an arrangement 45 whereby the side wall forming strip and the bottom forming member are so arranged and conformed that the two can be associated together by their own conformation and dimensions and without requiring any other connecting means or member and more particularly so arranged and conformed that the two can be associated together so as to provide the assembly with 50 an extension bottom to the receptacle.

55 Another object of my invention is the provision of an arrangement whereby the

side walls forming strip and the bottom forming member may each be given its predetermined outer surface characteristics and ornamentation while still in strip form and before they are shaped or formed for assembly purposes and before they are assembled so that the assembly of the two will give the completed and ornamented box structure.

Another object of my invention is the provision of an arrangement for forming a box of the character described in which irregularly shaped boxes can be made wholly by machinery and without the use of hand work.

The object generally of my invention is a method for forming a box construction with an extending bottom in which the number of parts are reduced to a minimum and therefore the steps necessary for their assembly also correspondingly reduced and all being capable of being formed by machine and the production of an improved box of the character desired at a minimum of cost.

While I have illustrated my invention in the drawings as employed in the manufacture of a heart-shaped box made up of a body section having an extension bottom and a cover section having an extension top, it will be understood that this is done merely for purposes of illustration and that my invention is not to be so limited except as called for by the claims.

For the attainment of these objects and such other objects as may hereinafter appear or be pointed out, I have illustrated in the drawings one form of my invention in which;

Fig. 1, shows in perspective the blanks and strips from which the parts of the box are to be formed;

Fig. 2 is a perspective view of these elements to form the box body and shaped to predetermined conformation and ready for assembly;

Fig. 3 is a vertical section through the two showing the step of assembly;

Fig. 4 is a view of the completely assembled box body;

Fig. 5 is a vertical section transversely of a completed box with the cover in position.

Boxes intended for candy and similar articles are generally made up so as to have an attractive appearance and this attrac-

tive appearance is attained generally either by giving to the box an attractive conformation or shape or an attractive surface ornamentation—generally both. Boxes of 5 this character are generally made of cardboard and one of the methods of giving to the box its attractive appearance is to provide the body member with an extending bottom and where desired to do likewise 10 with the top member.

In the illustrated embodiment I have shown both the top member and the bottom member, one as provided with an extending bottom and the other as provided with 15 an extending top and so arranged that the two telescope. As they are duplicates in all respects, the description of one will suffice for both and in this description, I will limit myself to describing merely the construction of the body member.

The body portion of boxes of this character is generally made of cardboard or similar material and comprise a bottom and an upstanding continuous side wall and to give 20 to such box construction an extending bottom, one of the methods employed has been as follows: A strip of material of predetermined length is so shaped as to provide the desired continuous upstanding side wall which may be circular, heart shaped or of 25 any other desired outline and a bottom member of an outline to correspond with that of the upstanding side wall is either pasted directly thereto or more generally fixed 30 thereto by means of an adhesive strip of tape which is secured partly to the bottom of the side wall and partly to the lower surface of the bottom member and where the box is to be irregularly shaped, as in 35 the heart shaped box of the illustrated embodiment of the drawings, it is found difficult if not impossible to apply this adhesive strip by machinery and hand application is necessary.

40 A second bottom slightly wider all around than the bottom already secured to the outwardly extending side wall is then pasted or otherwise secured to the bottom already fixed to the side wall so as to have the edges of the second bottom extend beyond the edges of the first mentioned bottom and beyond the side walls, thus providing the extending bottom.

45 Where an adhesive strip was used to secure the first mentioned bottom to the side walls, it will be understood that it was impossible to ornament or color the side walls before the box was fully completed because the application of the adhesive strip would necessarily cover this ornamentation and destroy the effect thereof. This method of manufacturing the box not only requires at least the number of parts indicated but also successive operations for their association. 50 In addition, the box so produced will in-

herently be open to the defects which result from its manner of assembly.

In the drawings, I illustrate my method of forming a box of this character and upon viewing Fig. 1 of the drawing, it will be observed that I employ a side wall 70 forming strip 10, cut from a predetermined length to form the outer wall of the box body which it is desired to form and that this strip already has its outer surface 75 ornamented as desired in any preferred or desired manner as by covering it with a colored paper or silk 11, it being understood that the ornamentation can be applied in any other manner. This strip 10 is then 80 given the outline or shape which it is desired that the box shall have and which at 15 in Fig. 2 is shown to be heart shaped. This shape or outline is given to the strip 15 by shaping in any desired or preferred manner 85 as by a pressing or moulding operation and either simultaneously with the shaping of this strip or either before or after where desired, the strip 15 is molded or pressed so as to provide the doubled over lip 16 90 projecting outwardly from its outer surface and on its inner surface, the groove 17. The bottom 18 of the box body is given an outline which will correspond to the shape which it is desired the box shall have and 95 which in the illustrated embodiment is heart shaped and is of such dimension that when the ends 19 and 20 of the strip 15 are brought together as in Fig. 4, the outer heart shaped edge 21 of the bottom 18 will 100 be received within the groove 17 and locked therein when the lip end 19 of the strip 15 is secured to the opposite free end of said strip 20 in any preferred or desired manner as by the brads 22. This bottom member 105 18 is also given its surface ornamentation as by being covered by ornamented or colored paper or silk 23 before its assembly. With the edge of the bottom 18 received and locked in the groove 17 as described, 110 the two walls 24 and 25 of the outwardly extending lip or flange 16 are now pressed together in any preferred or desired manner into close contact with and down upon the opposite faces of the continuous edge of 115 the bottom 18 in the manner shown in Fig. 5 so that the bottom 18 is firmly secured against removal. Where desired, the engagement between the outer continuous edge of the bottom 21 and the two walls 24 and 120 25 of the outwardly extending lip 16 may be made more secure by the use of adhesive either upon the inner surface of the walls 24 and 25 or upon either or both of the opposite surfaces of the continuous edge of 125 the bottom member 18.

125 By my invention, it will be observed that I am enabled to obtain a box with an extending bottom by the employment of but two members, namely, an upstanding wall form-

ing strip and a bottom member and that the ornamentation can be applied to these members while they are in strip form and before assembly and in fact, before they have 5 been cut from a continuous sheet and that the box thus produced requires not only a reduced number of elements but a reduced number of operations for their assembly.

Furthermore, the necessity for any hand 10 operation is completely eliminated even though the box may be irregularly shaped and in addition, the union between the bottom member and the side wall members will not only be a better one, but as the extending 15 edge is formed of three superposed layers, added strength and rigidity will be given to this portion of the box.

It will be understood that the groove 17 is formed by forcing outwardly the material 20 of the side wall forming strip, longitudinally thereof and along a line substantially parallel to the bottom and adjacent the bottom so that the two inclined walls 24 and 25 are formed of sufficient depth to permit 25 them to be pressed down upon and grip a substantial portion of the edge of the bottom so as not only to provide a bottom extension of substantial dimensions, but also to give a gripping engagement between these 30 walls and the edges of the bottom over a substantial area.

The shaping of the strip 10 so as to give 35 it the desired outline as shown in Fig. 2 and the provision therein of the groove 17 is preferably made in a single operation, as by the employment of appropriate moulding dies.

The presence of the outstanding lip 16 formed by the groove 17 not only serves the 40 purposes set forth, but also makes the up-standing wall more rigid and less likely to buckle and in addition, minimizes the warping tendency of the box.

Having thus described my invention, what 45 I claim is—

1. The process of forming a paper box construction having an extension end wall, which comprises the step or steps of simultaneously forming in the strip which is to 50 serve as the side wall of the box, a flange projecting from its outer face and a groove on its inner face, positioning said strip about the end wall member to have the strip form a continuous outer wall about the end wall 55 member with the edge of the latter received in the groove of the former, and forcing the opposite surfaces of the groove down upon

the opposite faces of the edge of the end wall member to cause the two to be secured together thereby along said edge. 60

2. The process of forming a paper box construction having an extension end wall, which comprises the step or steps of simultaneously forming in the strip which is to serve as the side wall of the box, a flange 65 projecting from its outer face and a groove on its inner face, positioning said strip about the end wall member to have the strip form a continuous outer wall about the end wall member with the edge of the latter received in the groove of the former, the said groove and said edge having had adhesive applied therebetween, and forcing the opposite surfaces of the groove down upon the opposite 70 faces of the edge of the end wall member to cause the two to be thereby secured together adhesively along said edge. 75

3. A paper box construction comprising an extension end wall member and a side wall member, said construction being formed by 80 providing a groove on the inner face of a strip of material, positioning said strip about the end wall member to have the strip form a continuous outer wall about the end wall member with the edge of the latter received in the groove of the former, and forcing the opposite surfaces of the 85 groove down upon the opposite faces of the edge of the end wall member to cause the two to be thereby secured together along 90 said edge.

4. As an element of a paper box construction consisting of a side wall member positioned about an extension disk bottom received in and engaged by a groove in said side wall member and secured thereto by said engagement, a strip having a groove formed in its inner face and so constructed and arranged as to form a flange extending outwardly from the outer face thereof and within which groove is to be freely received the edge of the disk bottom, said groove being so constructed and arranged that when the strip is positioned about the disk bottom with the disk bottom edge received in said groove, the faces of the groove can be pinched together about said edge so as to thereby secure the side wall and bottom wall together against separation. 95 100 105

In witness whereof, I have hereunto 110 signed my name, this 6th day of March, 1925.

ADOLPH KLEIN.
